UNITED STATES PATENT OFFICE

2,554,399

FIRE-RESISTANT DOOR FRAME

Frederick J. Bremer, Hamilton, Ohio

Application November 16, 1948, Serial No. 60,305

6 Claims. (Cl. 109—77)

1

The invention of this application relates to vault doors and more particularly to fire-resistant vault door frames on which the usual fire-resistant vault door is hung.

This application is a continuation-in-part of my copending application, Serial No. 629,755, filed November 20, 1945, now abandoned.

Fire-resistant vault doors as heretofore constructed, embodied a frame and door which were usually fabricated and assembled as a unit ready for installation. When these doors were installed in a vault, the assembled frame and door were mounted in an opening in the vault wall. This opening of necessity was larger than the door frame. After mounting the frame and its door in the opening, the frame would be adjusted by means of wedges and blocks until the door and frame were in a plumb position. These wedges and blocks were relied upon to hold the door and its frame in a plumb position during the time that the door frame was grouted in. After plumbing of the door and its frame, grout would be forced into the space between the door frame stiles and the door frame header and the walls of the opening in the vault wall. The grouting in of the door required much time and labor, several days often being spent in setting the frame and door. The grouting also resulted in much dirt and spoiled the finish of the wall around the door frame. The walls, therefore, had to be patched and refinished, all of which added to the expense of installing a fire-resistant vault door.

If, after the door frame had been grouted in, the door and frame shifted out of plumb for one reason or another, the door would require re-plumbing or resetting. Also, if later on the building settled and threw the door out of plumb, the door could not be reset to plumb position without tearing out the hardened grout. In other words, once the grout had set and hardened, not much could be done to readjust the door to a plumb position without a great deal of labor and expense.

From the above it will be seen that fire-resistant doors such as constructed in accordance with prior art practice, had no air space between the door frame stiles and header and the walls of the opening in the vault wall because it was completely filled up with grout. According to my invention I have provided a groutless door frame whereby a door frame with its door hung therein can be set in an opening in a vault wall and adjusted to a plumb position and secured in such position without the use of grout in the

2

space between the door frame stiles and header and the walls at the sides and top of the opening in the vault wall and which utilizes the space formerly occupied by grout as a useful heat-insulating dead air space. The door frame is so constructed that it can be mounted in a plumb position and secured in such position at the time of installation or easily readjusted to plumb position if at any future time something happened that would throw the door out of plumb position.

An object of this invention is to provide a fire-resistant vault door frame and door that may be fabricated complete at the factory and installed in a vault door opening after the walls have been fully finished and decorated without grouting in the door and without marring the decorative finish of the wall surface around the door frame.

Another object of the invention is to provide a completely assembled fire-resistant vault door frame and door provided with means for adjusting the vault door frame and its door to and securing it in plumb position and in spaced relation to the sides and top of the opening in the vault wall to thereby provide a heat-insulating dead air space.

Another object of the invention is to provide an assembled fire-resistant vault door frame and door of such construction that it may be mounted in an opening in a vault wall and secured in place without grouting, and which, when mounted in place, provides a dead air space between the exterior of the stiles and the header of the door frame and the walls at the sides and top of the opening in the vault wall.

A further object of the invention is to provide a door of the character set forth in the next preceding paragraph, in which the dead air space is filled with a heat-insulating material such as mineral wool or the like that may be placed in such space in a dry condition as distinguished from wet grout.

And a still further object of the invention is to provide a groutless type fire-resistant door frame that may be easily adjusted to a plumb position if the frame and its door after installation, have shifted out of plumb for one reason or another.

These and other objects of the invention will in part be apparent and will in part be obvious from the following description, taken in conjunction with the accompanying drawings, in which:

Figure 1 is a view in front elevation of a vault door and frame embodying a form of the inven-

tion, the door and frame being mounted in a door opening in a vault wall;

Fig. 2 is a view in section, taken on line II—II of Fig. 1, showing the construction of the door stiles and a means for adjusting the door frame and its door to and securing it in a plumb position;

Fig. 3 is a view in vertical section taken on line III—III of Fig. 1, showing the construction of the door frame and header and means adapted to co-operate with the means provided for the door frame stiles for adjusting the door frame and its door to and securing it in plumb position;

Fig. 4 is a view in elevation from the vault side of one of the door frame stiles and a part of the header and sill, the rear closure plates being removed; and

Figs. 5 and 6 are views in section showing a modified construction of the door frame stiles and header and securing means therefor.

Throughout the drawings and specification like characters indicate like parts.

In Figure 1 of the drawings the front of a vault wall 1 is shown provided with an opening 2 therein in which a vault door frame 3 is mounted. A vault door 4 is shown hung on hinges 5 in the door frame. The door frame 3 and its door 4 are preferably fabricated and assembled as a unit ready for installation in a vault. The door 4 and its frame 3 are of the type known as high temperature fire-resistant doors. The door 4 may be of conventional fire-proof construction. The frame 3 is so constructed that the time required for installing a high temperature fire-resistant vault door is reduced to a matter of hours, as distinguished from days, and it may be installed after the wall surface surrounding the vault wall has been finished, that is, plastered and painted, or otherwise decorated, without in any way marring the finish of the walls. The construction of the door frame is such that the door frame and its associated door 4 may be adjusted to and secured in a plumb position without the use of grouting materials and which makes possible at any future time after installation, the readjustment of the door to a plumb position, should the door and its frame for one reason or another, be thrown out of plumb or alignment.

Door frame 3 comprises a sill 7, stiles 8 and 9 and a header 10. The door sill 7 as shown, may comprise a heavy steel plate which rests on the bottom of the opening in the vault wall. The vault wall construction may, as shown, be of concrete. The thickness of the wall is determined by the number of hours that the vault is to resist the heat of a fire. In forming the opening for the vault door frame and its door, the floor on which the sill rests may be made as level and smooth as it can be. The dimensions or size of the opening will be made larger than the door frame so that the door frame and its door may be positioned within the door opening.

The door stiles 8 and 9 and the header 10 are, as shown, constructed in substantially the same fashion, that is, the transverse section of each is substantially identical. The door stiles and the header are hollow within which safe insulation 12 may be confined. Each door stile and header is fabricated from steel plates and welded at various points to each other and to the sill so that a rigid strong frame is provided. As door stiles 8 and 9 are substantially similar, a description of one will be sufficient, similar parts in the other being designated by the same reference characters.

Door stile 8 comprises an upright 13 having a series of inclined faces and grooves therein shaped to conform to the contour of the adjacent side of door 4 for purposes well understood in this art. The inner end of the jamb 13 is of Z-shape, so as to provide an abutment or keeper 14 for a locking bolt 15. Immediately inside the jamb 13 is a member 16 of substantially L-shape, one leg of which is welded to a flange 17 of the jamb member 13. It will be observed that the contour of the jamb member of stile 8 differs some from that of stile 9 to the extent necessary for it to conform to the surface of the hinge side of door 4. Stile 8 also includes an upright 19, the forward or outer portion 20 of which is of channel shape and the inner portion 21 of which is of substantially L-shape, the two portions being joined by one side 22 of the outer channel. The front portion 20 is disposed relatively close to the adjacent wall of the opening in the vault wall while the inner portion 21 is spaced a substantially greater distance from the vault wall, to provide working space for tools employed in setting the door as will be explained later. The front of stile 8 is provided with a plate 24 which is welded or otherwise secured to the front flanges of jamb member 13 and the upright 19. This plate extends across the space between the stile and the wall at the side of the opening in the vault wall and abuts the surface of the vault wall, thereby concealing this space and closing it at the front of the door frame. The rear of the door stile members 16 and 19 are flanged as at 26 and 27 to serve as abutments for a closure plate 28. The closure plate 28 may be secured to the flange 27 of the stile plate 19 by means of bolts 30 that are threaded into nuts 31 welded to the flange 27.

The header 10 comprises a jamb member 33 which is shaped to conform to the contour of the top edge of the vault door 4. To the inner end of the jamb member 33 is welded or otherwise secured a member 35 of substantially L-shape. The header also includes a structural member 36 having a front portion 37 of substantially channel shape and a rear portion 38 of substantially L-shape, the two portions being connected by a side 39 of channel 37. The structural members forming the header, as can be seen by inspection of the drawings, conform in shape substantially to the shape of the structural members comprising the door stiles 8 and 9. The ends of structural members of the header meet the upper ends of the structural members of the door stiles, as shown in Fig. 4, being welded or otherwise secured at their junction points. The front of the header 10 is provided with a plate 40 which is welded or otherwise secured to the front flanges of channel member 37 and jamb member 33. Plate 40 as shown, extends upwardly so as to abut the front surface of the vault wall and conceal the space between the wall of the opening in the vault wall and header member 36. As shown in Fig. 3 the inner portion 38 of the header member 36 is offset with respect to the front portion 37 so that a relatively wider space is provided between the vault wall and portion 38, than between the vault wall and the front portion 37, to provide working space for tools as will later be explained.

The header constructed as above described, is hollow within which safe insulation may be confined. The back of the header may be closed by means of a plate 42 secured to a flange 43 on offset portion 38 by means of bolts 44 threaded

into nuts 45 which are welded or otherwise secured to the flange 43.

Fig. 4 is a rear view or a view from the vault side of the door, closure plates 28 and 42 being removed to show the hollow spaces within the header and the door stiles and that these spaces communicate with each other, and the spaces between the outer structural members of the door stiles and header and the adjacent walls at the opening in the vault wall and that these spaces communicate with each other.

The means employed for securing the door frame in the opening in the vault wall to maintain and effectuate a confined or enclosed heat insulating space between the door frame stiles and header and the walls at the sides and top of the opening in the vault wall, may be variously constructed and take various forms. In Figs. 2, 3 and 4 jacks are shown as a means for securing the door frame in the vault wall opening to provide the spacing of the door frame from the vault wall while in Figs. 5 and 6 I have shown a modified form of securing and space-closing means.

In order that the door frame and its door may be mounted in the opening in the vault wall without grouting the same in, as in the case of prior art doors, means are provided in conjunction with the door stiles and the header whereby the door frame may be adjustably secured to the walls at the sides and top of the opening in the vault wall in a plumb position.

In the form of securing means shown in Figs. 2 to 4, each door stile is provided with a plurality of jacks 47 located at spaced points in the height of the door stiles in the relatively wide space at the rear thereof so that there will be sufficient room or space to apply tools thereto. The jacks may be in the form of screws threaded through nuts 48 secured to the offset portions 21 of the door stiles as by welding. The outer ends of these screws are provided with bearing heads 49 shaped to receive a wrench or suitable tool for turning the jacks during adjustment and securing of the frame. If desired, lock nuts 50 may be provided for locking the jacks in place once the door frame and its door have been adjusted to and secured in plumb position. The upper structural member 36 is likewise provided with a plurality of jacks 47. These jacks are mounted on the offset portion 38 of member 36 and comprise screws threaded through nuts 48 which are welded or otherwise secured to the portion 38. The ends of these screws adjacent the vault wall opening may be provided with enlarged heads 49 shaped to accommodate a wrench or other suitable tool. Also if desired, lock nuts 50 may be employed for locking the jacks in any desired position.

When an assembled frame having a door therein, is to be mounted in the opening of a vault wall, the rear plates 28 and 42 are removed and the jacks are retracted so that the heads 49 thereof will not interfere with the walls of the vault door opening when the frame and door are being inserted into the same. A frame with its door is then slid into the opening in the vault wall from the front thereof until the marginal plates 24 and 40 abut the front surface of the vault wall. The door and frame are then shifted until a uniform space obtains between the outer edges of the door stiles and the adjacent walls of the opening in the vault wall. The jacks of the door stiles and header are then turned until the heads thereof engage the vault walls and the door is tested for plumb with the door 4 in

closed position. The door is also swung to wide open position and the frame and door are again checked for plumb. The jacks 47 are then adjusted at various points around the door frame as may be required to attain the desired plumb condition of the door and frame when the door 4 is closed, as well as when it is wide open. When this plumb condition has been achieved the jacks are tightened uniformly until the frame is firmly secured in plumb position.

It will be apparent that as the jacks are tightened during the plumbing of the door, that stresses and strains will be set up in the outer stile members and in the upper member 36 of the header. To resist this strain and to make the header and the stiles more rigid, struts 51 are provided in the door stiles and struts 52 are provided in the header. These struts are secured adjacent the jacks and span the space between the inner and outer structural members of the stiles and the upper and lower members of the header. The struts may be welded or otherwise secured to the door stiles and header members to give sufficient rigidity.

The door frame securing means shown in Figs. 5 and 6 is such that the portions 21 and 38 of the stile and header members 19 and 36, respectively, need not necessarily be offset. In the form shown in Figs. 5 and 6 the border plates 28 and 42 in conjunction with bolts 53 anchored in the vault wall on the vault side thereof, are employed to secure the door frame and door in a plumb position in the wall opening and to maintain the stiles and header of the frame in spaced relationship to the walls at the sides and top of such opening. These plates serve also to close this space at the vault side of the door frame as well as the openings in the vault sides of the stiles and header.

The border plates 28 and 42 are secured to members 19' and 36' of the stiles and headers by bolts 39 and 44 as in the form shown in Figs. 2 to 4. When so secured a space S remains between the rear edges of spaces between the vault wall and the sides and top of the frame. At the outer edges of plates 28 and at the top edge of plate 42 enlarged openings or slots 54 may be provided to accommodate the bolts 53. These openings are of such size and shape that the door frame may be adjusted to a plumb position and to establish the spacing between the vault wall at the sides and top of the opening therein. When this adjustment has been made, the nuts on anchor bolts 53 are drawn up tightly whereby the border plates are firmly clamped to the vault wall. By tightening bolts 39 and 44 the necessary extent, the door frame is pulled inwardly to the extent necessary to firmly clamp the border plates 24 and 40 against the front of the vault wall. The pressure of the front border plates on the vault wall aids in holding the door frame and door in a secure position.

When the door frame is secured, a tight dead air space is effected between the door frame and the walls at the sides and top of the opening in the vault wall. This air space is an effective heat insulator. Its insulating properties appear to materially improve when steam permeates into it from the insulation confined within the header and stiles of the frame. This steam develops when the door frame is exposed to a hot fire. Since the joints between the various structural members of the stiles and header are not pressure tight the steam can escape into the space. At high temperature steam or vapor can also be

given off by the vault wall which partially bounds this space. The space between the door frame and the vault walls may also be filled with a dry insulating material such as mineral wool or other materials as described in connection with Figs. 1 to 4 inclusive.

The insulation confined within the hollow of the door stiles and the header may be of any standard safe fire-resistant insulation. Materials used for this purpose are usually monolithic substances containing relatively high percentages of cement, vermiculite, diatomaceous earth and similar materials. The insulation confined within the door stiles and the header usually contains a substantial amount of moisture. Under high temperature this moisture is evaporated into steam. This steam can escape from the hollow space of the header and stiles into the confined space between the outer members of the stiles and the adjacent walls of the vault opening and the space between the upper member of header and the adjacent wall of the vault opening. The flange plates at the front and rear of the door frame tend to confine the steam within the space between the vault wall and the door frame and this is believed to add materially to the heat insulating properties of the space between the outer stile members 19 and the upper header member 36.

The space between the door frame and the walls of the opening in the vault wall may be utilized as a dead air space or it may be used as a space for confining a dry, fibrous insulation such as mineral wool, or the like; or the insulation may be a dry vermiculite, either calcined or raw, or consisting of a mixture of raw and calcined vermiculite. After the insulation has been properly placed, the plates at the rear or vault side of the door may be mounted in place and secured to the door stiles and header.

If after the door frame and its door have been installed and the frame and door are thrown out of plumb for one reason or another, as where the building settles, for example, the door frame can be readjusted to plumb by the means herein disclosed and described.

Having thus described the invention, it will be apparent to those skilled in this art, that various modifications and changes may be made without departing either from the spirit or the scope thereof. Therefore, what I claim as new and desire to secure by Letters Patent, is:

1. A fire resistant vault door adapted to be placed in assembled condition into a door opening in a vault wall and secured therein in plumb position without grouting the door, said door having a frame comprising a sill, stiles and header all rigidly secured together, the stiles and header being fabricated from shaped steel plates to provide a hollow space therein for containing heat insulation, the rear portions of the stile plates adjacent the vault wall opening being offset away from the vault wall to provide working space for tools accessible from the vault side, screw jacks having screw thread support with the offset portions of said stiles and headers and being disposed to be actuated at substantially right angles to the walls of the opening in the vault wall into and out of engagement with the same whereby by adjusting the relative forces exerted by said screws on the adjacent vault walls the door frame may be adjusted to and secured in plumb position and also provide an air space between said stiles and header and the walls of the opening in the vault wall, the front and rear

of said stiles and headers being provided with border plates adapted to abut the surface of the vault wall surrounding said door to close and conceal the space between the walls of the opening in the vault wall and the door frame.

2. A door according to claim 1, characterized by the fact that the vault side of said stiles and header are provided with removable plates whereby access may be had to the hollow interiors thereof to fill the same with insulation.

3. A door according to claim 1, characterized by the fact that the vault side of said stiles and header are provided with removable plates that abut the wall surfaces surrounding the door on the vault side to render the tool space for said jacks and the hollow interiors of said stiles accessible for adjusting the jacks and filling the stiles and header with insulation.

4. A door according to claim 1, characterized by the fact that the vault side of said stiles and headers are provided with removable plates whereby access may be had to the hollow interiors thereof to fill the same with insulation, and insulation in the air space between the door stiles and header and the adjacent walls of the opening in the vault wall.

5. A fire-resistant vault door frame adapted to have a fire-resistant door hung therein, said frame having hollow steel stiles and a hollow steel header and a steel sill all secured together as a rigid structure, fire-resistant safe insulation containing moisture substantially filling the hollow space of said stiles and header, the door frame being disposed for mounting in a door opening in a vault wall the dimensions of which are such that when the frame is placed in the opening a space between the walls of the vault wall opening and the adjacent sides of the door stiles and the top of the header is provided, border plates extending around the periphery of and being secured to the fronts of the door stiles and header, said plates extending laterally of the frame so as to abut the wall surface surrounding the opening in the vault wall and close the space between said stiles and header and the vault wall at the sides and top of the opening therein, steel border plates at the vault side of said frame and secured thereto, said plates spanning the spaces between the door frame and vault wall and abutting the surface of the vault wall surrounding said space, said front and vault side border plates closing said space to render it effective as a heat insulating dead air space and as a retainer for steam escaping into the same from the insulation in the stiles and header when the frame is exposed to high temperatures, and means adapted to coact in said opening with the sides and top thereof for securing said frame in the said opening to maintain the spacing between the sides and top of said frame and the sides and top of the vault wall opening and for adjusting at will said door frame for plumb.

6. The combination with a fire-resistant vault wall having a rectangular opening therein for a door, of a fire-resistant door frame having a door hung therein, the sides and top of said door frame being provided with means adapted to coact with the sides and top of said rectangular opening for securing said frame in said opening in spaced relation to the sides and top of said rectangular opening and for adjusting at will said door frame for plumb, the door frame comprising hollow steel stiles and a hollow steel header, fire-resistant insulation containing moisture substantially filling said stiles and header, and steel plates

around the sides and top of said door frame at the front and vault sides thereof abutting the stiles and header and the wall surfaces surrounding said opening thereby completely enclosing said space between the sides and top of the door frame and rendering said space effective as a heat barrier and as a space into which steam can escape from said insulation in the stiles and header to supplement the heat insulating properties of said space.
